UNITED STATES PATENT OFFICE.

THOMAS M. FERGUSON, OF SUCARNOCHEE, MISSISSIPPI.

HORSE-DETACHER.

SPECIFICATION forming part of Letters Patent No. 310,808, dated January 13, 1885.

Application filed April 17, 1884. (No model.)

To all whom it may concern:

Be it known that I, THOMAS M. FERGUSON, a citizen of the United States, and a resident of Sucarnochee, in the county of Kemper and State of Mississippi, have invented certain new and useful Improvements in Horse-Detachers; and I do hereby declare that the following is a full, clear, and exact description of the invention, which will enable others skilled in the art to which it appertains to make and use the same, reference being had to the accompanying drawings, which form a part of this specification, and in which—

Figure 1 is a rear elevation of my improved horse-detacher, showing the detaching-levers depressed in their normal position. Fig. 2 is a rear elevation of the same, showing the detaching-levers elevated or opened by their operating-cord in order to permit the cock-eyes of the traces to slip off of the outer ends of the trace-holding pins; and Fig. 3 is a longitudinal horizontal sectional view of the device in its closed position.

Similar letters of reference indicate corresponding parts in all the figures.

My invention relates to that class of horse-detachers in which the cockeyes on the rear ends of the traces may be readily released from the ends of the single-tree by a single movement of the driver's hand; and it consists in the improved construction and combination of parts of a device of the above-described class, as will be hereinafter more fully described, and particularly pointed out in the claim.

In the accompanying drawings, A represents the single-tree proper, upon each end of which are secured the metal caps B, provided at their outer ends with the recess B' and slot 40 B'', for the purpose herein specified.

Within the longitudinal recess B' of each cap B is pivotally secured, at the outer end of the said recessed cap, the trace-holding pin C, which is of such a length that that portion of it which lies within the recess B' is about four times the length of the projecting end upon which the cockeye of the trace fits. The recess B' is preferably about twice the depth at its inner end that it is at its outer end, so that 50 the inner extremity of the pivoted pin C lies

back or clear of the pivoted operative end of the detaching-lever D.

D D indicate the detaching-levers, each of which is provided at one end with a cam, D', which is eccentrically pivoted within the slot 55 B'' in such a manner that when the outer free end of the said lever is depressed the cam will serve to lock the inner end of the trace-holding pin within its recess, while when the outer end of the lever D is raised or elevated the inner free end of the pin C will be allowed to swing out of its recess. The outer end of the lever, which extends beyond the end of the cap B, is bent down at right angles, so as to extend immediately in front of 65 and at right angles to the outer end of the trace-holding pin, so as to prevent the cock-eye from slipping off of the said end when the lever is depressed in its normal position. The outer ends of the detaching-levers are connected by an operating cord or strap, E, from the center of which a second cord or strap, F, extends back within easy reach of the driver's hand.

From the foregoing description, taken in 75 connection with the accompanying drawings, the construction of my improved horse-detacher will readily be understood without requiring further explanation.

It will be seen that the outer end of the levers D may be readily lifted to admit of the cockeyes of the traces being slipped upon the outer ends of the trace-holding pins C, when the levers may be again depressed, and the cams on their inner ends will serve to hold or 80 lock the pins C firmly in their closed position, while the downwardly-projecting ends of the levers will prevent the cockeyes from slipping off of the outer ends of the pins.

It will be seen that by constructing the inner 90 portion of the pivoted pins C of a much greater length than their outer ends the holding-cams of the levers D will have a great leverage in holding the said pins in their locked position.

In order to detach the horse from the vehicle the driver merely pulls upon the single operating cord or strap F, thereby through the intervening cords E E raising the outer ends of the levers D D into a vertical position, as shown in Fig. 2 of the drawings, when the 95 100

inner ends of the trace-holding pins will be permitted to swing out, so as to allow the cockeyes of the traces to slip off of the ends of the said pins, thereby readily and easily 5 freeing the horse from the vehicle.

Having thus described my invention, I claim and desire to secure by Letters Patent of the United States—

As an improvement in horse-detachers, the 10 combination, with a single-tree provided with metallic caps, each of which is provided with a longitudinal recess and a vertical slot opening down into the said recess near its inner end, of the trace-holding pins pivotally secured within the said recesses, detaching-levers 15 provided at their inner end with cams adapted to be pivoted eccentrically within

the vertical slots of the metallic caps, and having their outer ends bent down at right angles, so as to extend immediately in front 20 of the outer ends of the trace-holding pins, and operating-cords extending from the outer ends of the detaching-levers to a point within easy reach of the driver's hand, all constructed and arranged to operate substantially in the 25 manner, and for the purpose shown and set forth.

In testimony that I claim the foregoing as my own I have hereunto affixed my signature in presence of two witnesses.

THOS. M. FERGUSON.
